UNITED STATES PATENT OFFICE.

EDWARD T. BUTLER, OF BELLEFONTAINE, OHIO.

CLOTH-MEASURING MACHINE.

SPECIFICATION forming part of Letters Patent No. 589,160, dated August 31, 1897.

Application filed April 7, 1897. Serial No. 631,122. (No model.)

To all whom it may concern:

Be it known that I, EDWARD T. BUTLER, a citizen of the United States, residing at Bellefontaine, in the county of Logan and State of Ohio, have invented certain new and useful Improvements in Machines for Measuring Cloth; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improved machines for measuring cloth or similar goods in the piece at any time without the necessity of unwinding or the use of the ordinary yardstick.

The invention consists in the combination, 20 with a frame having mounted therein a fold-indicating slip divided by transverse lines and consecutively numbered, of a fixed arm at one end of the frame, a sliding arm, a pointer or indicating-hand carried by the sliding arm and registering with a scale to indicate the width of the piece, and a movable indicating device divided into columns numbered at the head to correspond with the width-indicator, and each column containing 25 figures to indicate the yards and fractions of yards, and a movable indicating-hand or pointer to register with both the fold-indicating slip and the movable yard and inch indicator, and to certain other novel features 30 hereinafter described.

In the accompanying drawings, Figure 1 is a perspective view of the device complete, showing a piece of goods in position to be measured. Fig. 2 is a plan or top view of the 35 same. Fig. 3 is a transverse section through one end of the machine, showing one manner of operating the movable yard and indicating device, also one manner of mounting the sliding arm for indicating the width of the fold.

The casing A, in which the parts are mounted, consists, preferably, of a rectangular box of any desired length and width, with the bottom board extending out beyond the front 40 face, as shown at A³, or having a separate strip attached thereto, for a purpose herein-after explained. Near each end of the ma-

chine are legs or supports B B' of suitable length to elevate the machine above the cloth-supporting table to permit the reception of a bolt of cloth or like fabric of large bulk between the table and the bottom of the casing. 55

The bottom A' is provided with a slot A³, running longitudinally of the machine, in 60 which slot is mounted a sliding arm C, which carries an indicating-hand or pointer D, extending through a longitudinal opening or slot D' in the front frame-piece. A rod E is secured in suitable brackets E', extending 65 up from the frame, and upon which rod is pivotally mounted a pointer or indicator-hand F, having a rear extension or thumb-piece F'. This rear or thumb piece is preferably made of sheet metal, with the lugs to 70 form the pivotal bearings bent down, and which lugs are constructed in such manner as to engage a notched bar G, formed in or attached to the upper edge of the front frame-casing, and which notches are spaced to correspond to the fold-indicating strip. This 75 fold-indicating strip extends longitudinally from near each end of the machine and is divided into spaces consecutively numbered, and the pointer being moved on the rod after 80 the number of folds in the bolt has been ascertained opposite or in line with such number on the strip.

The projecting edge of the frame A³ is provided with a plate or strip divided into sections preferably one-eighth of an inch apart, with a series of figures of like numbers consecutively arranged, each number representing the quarter of a whole—viz., "7," "7₁," "7₂," "7₃," "8," "8₁," &c.—as shown at D², 85 90 and represent the width of the bolt of goods, the same being indicated by the pointer D, carried by the sliding arm C, the movement or play of the pointer or hand being controlled by the engagement of the arm with the bolt 95 of cloth or goods.

Mounted in the frame and running longitudinally thereof are rollers I, geared together, one shaft of which is provided with a crank or handle I' for permitting said rollers to be rotated in either direction by the crank. Where the sheet is short, or if the sheet is so long as to affect the movement of the roll relative to the gears, said gears may be dispensed with 100

- and the crank changed from the shaft of one roll to the shaft of the other. To these rollers is secured a sheet L of paper, cloth, linen, or like material, preferably about twenty-four 5 inches wide and forty inches long, divided into columns, each column being headed with a figure which corresponds in order with the figures on the width-scale and with the columns divided in sections and numbered with 10 a series of figures of like number consecutively arranged, each of the series representing the number of yards and fractional part thereof, the sheet of the dimensions described containing upward of ten thousand different 15 calculations. This sheet may run over a bar M, extending from end to end of the machine, or over a roller or idler, and the face or numbers, as also numbers to indicate the folds, being covered with glass to protect them from 20 injury.
- To ascertain the number of yards and fractions or inches, after counting the folds the pointer F is carried on the rod E until it registers with a corresponding number on the 25 column H, and is then engaged with the notches G to hold it stationary. The sliding arm is then moved against the bolt or piece of goods resting upon one edge or side against the leg B', and the pointer D will indicate on 30 the scale D² the width of the goods or fold thereof. The crank is then turned to revolve the rollers to expose the column on the sheet having the head-number corresponding to the number indicated by the pointer D or the 35 width-indicator, when the figures on the column opposite or in line with the pointer F will indicate or show the whole number of yards and inches contained in the piece or bolt.
- 40 Having now described my invention, what I claim as new, and desire to secure by Letters Patent, is—
1. In a machine for measuring cloth in the bolt, the combination of a fold-indicating slip 45 divided or sealed, and having consecutive numbers, a sliding arm having a pointer, a

scale with which the same registers, a movable sheet divided into columns, the head of each column numbered correspondingly to the number on the scale, and with numbers 50 to indicate the yards and fractions of yards, and a movable hand or pointer to register with both the fold-indicating slip and the movable yard and inch indicator, substantially as, and for the purpose set forth. 55

2. In a machine for measuring cloth in the bolt, a frame the supports therefor, a fold-indicating slip divided or sealed and consecutively numbered, a sliding arm carrying a pointer, a plate or strip divided into sections 60 with a series of figures of like number, consecutively arranged, and each number representing the quarter of a whole, a pair of rollers carrying a sheet divided into columns, each column being headed with a figure which 65 corresponds in order with the figures on the plate and with the column divided into sections and numbered with a series of figures of like number consecutively arranged, and a movable hand or pointer to register with 70 both the fold-indicating slip and the numbers on the column of the movable sheet, substantially as and for the purpose set forth.

3. In a machine for measuring cloth in the bolt, a fold-indicating slip, a sliding arm carrying a pointer, a scale with a series of figures of like number consecutively arranged, a movable sheet divided into columns and numbered substantially as described, a movable pointer and means for setting and holding the same registered with the fold-indicating slip, and means for moving the sheet to expose a column numbered to correspond with the number indicated by the pointer on the fold-indicating slip, as and for the purpose 85 set forth.

In testimony whereof I affix my signature in presence of two witnesses.

EDWARD T. BUTLER.
